6034 X Phileno Payne and Joshua Randall of Clarion, Mississippi
Letters Patent.

The Office aforesaid to whom Letters Patent and making best of the same, containing a description in the words of the said Phileno Payne and Joshua Randall themselves of their improvement in the Process for carding Cotton and other soft fibrous substances.

It is Known, That the Phileno Payne and Joshua Randall of Fort Gibson, Oklahoma, in the State of Mississippi, have made an improvement in the process for pressing cotton and other soft fibrous substances which is described as follows. The Card consists of the following parts, viz.

1. The Frame. 2. The Follower and Posts. 3. The carriage or ways. 4. The Toggle-jointed Carous. 5. The horizontal shafts and gearing. - 1. The Frame consists of two posts about twenty feet high, framed into a side and cap piece of sufficient strength to sustain the required pressure. Also two side pieces about twenty feet long and ten by sixteen inches thick, which may be either framed with a separate end piece or into the frame of a house to support the carriage or ways, and gearing to be hereafter described. 2. The follower and Posts. The Posts or Stirrups are framed into a head piece by making the heads of the posts lap over the head piece inward. The lower ends have projections outward, on which the ends of the levers hereafter described work. From the head piece is suspended the follower, hung on hinges, and which is made sufficiently long to press down the cotton or other substance without opening the Box. Grooves are left on the lower side to allow the ends to pass.

3. The Ways or carriage are about twenty five feet long of sufficient size and strength to receive and support the levers to be hereafter described. On the lower side and about seven feet along the outward end are cogged racks for receiving the cogs placed on a horizontal shaft. These ways are supported on the horizontal shaft, and have friction rollers placed over them to keep them in place. 4. The Toggle-jointed Carous.

These are made by preparing four pieces of good ash, oak or any suitable timber about eight or ten feet long and eight inches square made a little smaller at each end to receive the iron to be described. At each end of each lever is inserted a piece of cast or wrought iron, about 14 inches long, 2 inches thick, 6 inches wide and having at the lower end a circular head on which it turns. The iron is let into the lever by a T head, which keeps it fast when working up and down. On each side of the circular head are wedges to work in. These placed in the head & set and on each side of the ways. These pieces of iron with circular heads and wedges are fastened to the ways by strips or belts of iron. 5. The Horizontal Shaft and Gearing. A horizontal shaft is made of a length equal to the width of the frame, and having on judgements and horns. On each end ^{is made} a cog wheel working on the racks on the under side of the ways, and a toothed cogwheel in the center working into a cogwheel on the driving shaft. Operation. The cotton or

substance to be prepared being placed in the box in the usual way. The main shaft is turned by animal or other power; the cog wheel on the upright shaft turns the bevel wheel on the horizontal shaft which causes the cog wheels on its ends to work in the racks of the ways and draw them over; these now being forward and straight in the toggle jointed levers which press down the follower with the cotton in the box. The rods are then inserted thro the openings on the lower side of the follower and the baton tied. When this process is used for preparing cotton, the part, or stamps, may be dispensed with, and the toggle jointed levers applied immediately to the follower. The box may also be dispensed with. What we claim as our invention and for which we solicit a patent is the before described machine for preparing cotton or other soft-fibrous substances. Further to illustrate our invention we refer to the model and drawing of the same deposited in the Patent Office.
